Filed May 4, 1970, Ser. No. 22,800

Term of patent 14 years

Int. Cl. D23—03
U.S. Cl. D23—127

FIG. 1 is a perspective view for a corner rail for use on fin-and-tube baseboard heating elements, showing my new design;

FIG. 2 is an enlarged sectional view taken on line 2—2 of FIG. 1;

FIG. 3 is an enlarged side elevational view thereof as viewed from the left of FIG. 2; and

FIG. 4 is a perspective view thereof on a reduced scale, the fin-and-tube heating element and second corner rail being shown in broken lines for illustrative purposes only.

The rail is broken away in FIG. 1 to indicate indeterminate length and is fragmentarily shown in FIGS. 3 and 4 for convenience of illustration.

I claim:

The ornamental design for a corner rail for fin-and-tube baseboard heating elements, as shown and described.
